CLOTHING DISPLAY RACK

Harry A. Robbins, 1516 Vermilion St.,
Danville, Ill. 61732

Filed Sept. 12, 1966, Ser. No. 3,819

Term of patent 14 years

(Cl. D80—10)

FIG. 4

FIG. 5

FIG. 1 is a front elevational view of a clothing display rack showing my new design;

FIG. 2 is an elevational view taken from one end thereof;

FIG. 3 is an elevational view taken from the end opposite from that shown in FIG. 2;

FIG. 4 is a top plan view thereof; and

FIG. 5 is a prospective view thereof.

The dominant features of my design reside in the portions shown in full lines, it being understood that the broken line representation of clothing in FIGS. 1 and 5, and the broken line representation of another identical clothing display rack in back-to-back relationship therewith in FIG. 5 are for purposes of illustration only.

What I claim is:

The ornamental design for a clothing display rack, as shown and described.
